UNITED STATES PATENT OFFICE.

JOSEPH KLEIDMANN, OF NEW YORK, N. Y., ASSIGNOR TO AUTO PAPER FEEDER COMPANY,
OF NEW YORK, N. Y., A CORPORATION OF NEW YORK.

ATTACHMENT FOR FEEDING-MACHINES.

No. 904,266.

Specification of Letters Patent.

Patented Nov. 17, 1908.

Application filed March 28, 1907, Serial No. 365,161. Renewed April 25, 1908. Serial No. 429,250.

To all whom it may concern:

Be it known that I, JOSEPH KLEIDMANN, a subject of the Czar of Russia, and a resident of the city of New York, borough of 5 Brooklyn, in the county of Kings and State of New York, have invented a new and Improved Attachment for Feeding-Machines, of which the following is a full, clear, and exact description.

10 This invention relates to attachments for feeding machines, and is particularly useful in connection with devices of this character used for the purpose of feeding sheets of paper into printing presses, ruling-machines 15 and the like.

The object of the invention is to provide a device of this character adapted for use in connection with feeding machines, and by means of which the table carrying the stack 20 of sheets of paper or the like is elevated as required, when the sheets are being segregated and fed into the printing press or other machine.

A further object of the invention is to provide 25 a device of this character by means of which the table is automatically elevated as the stack of sheets upon the table decreases, and by means of which a gradual and uniform upward pull is exerted upon the table 30 at different points of the same.

The invention consists in the construction and combination of parts to be more particularly described hereinafter and fully set forth in the claims.

35 Reference is to be had to the accompanying drawings forming a part of this specification, in which

Figure 1 is a side elevation of a feeding machine having my attachment, and showing parts in cross-section; Fig. 2 is an end view of the device, showing parts broken away; and Fig. 3 is an end view of a detail.

40 Before proceeding to a more detailed explanation of my invention, it should be understood that to attain accuracy in feeding and adjusting the sheets from the feeding machine to the printing press, ruling machine or the like, it is necessary that the stack of sheets be maintained at substantially the 45 same height, to enable the feeding mechanism to segregate the sheets and pass them from the stack uniformly and accurately.

50 My invention is applicable to feeding ma-

chines of various types in which a vertically 55 slideable table is used to carry the stacks of sheets.

Referring more particularly to the drawings, 1 represents the frame-work of a feeding machine having the uprights 2 and 3, between which is slidably mounted a table 60 4. Rotatably mounted upon the uprights 4 are grooved pulleys 5 and 6, and double grooved pulleys 7 and 8. An endless line 9 comprising a cord or other suitable member is arranged between the supports at each 65 side of the table and each line has upwardly disposed loops 10 and 11 passing over the pulleys 5 and 6, respectively, and over the double pulleys 7 and 8. Similar runs 12 and 13 of the upwardly-disposed loops 10 70 and 11 are rigidly secured to the table 4. As the runs of the upward loops of the endless line which is secured to the table 4 move in the same direction when the table is elevated, a like pull is exerted upon the table 75 at four different points when the table is moved upwardly or when one of the runs secured to the table is moved upwardly. By this arrangement the sliding movement of the table is smooth, and there is no possibility of jamming the sliding table in its 80 guides.

The similar uprights 3 have lateral extensions 15 in which is rotatably mounted a shaft 16. The shaft 16 carries a member 17 85 mounted to swing thereupon and having an arm 18 provided with a roller 19 adapted to engage the stack of sheets 20 and normally to rest upon the top of the stack. The sheets are fed from the stack by means of proper 90 mechanism 25 over the lip 21 on to a feed conveyer 22, which transports the sheets to the printing press or other machine. The member 17 further has an arm 23 at an angle with the arm 18 and having at its end a 95 roller 24.

A second shaft 26 is rotatably mounted upon the similar opposite uprights 3 and has at one end a sprocket 27. By means of the sprocket 27 and a chain 28 the shaft 26 100 is operated from the driving mechanism of the printing press or other machine to which my invention is applied. Rigid upon the shaft 26 is a cam 29 engaging with the roller 24 of the member 17 and having a recess 30 105 adapted to receive the roller 24. A second

cam 31 is rigidly mounted upon the shaft 26 adjacent to the cam 29 and corresponds substantially in form to the first cam. The cam 31 has a recess 32 corresponding to the 5 recess 30 of the cam 29.

A shaft 33 is rotatably mounted above the shaft 26 upon the uprights 3 and has rigid worms 34. Loosely mounted upon the shaft 33 between the worms 34 is a lever 35 10 having a lateral extension 36 engaging the cam 31, the recess 32 of which is adapted to receive the extension 36. Beyond the extension 36 the lever has a laterally disposed end 37 carrying a lateral integral pin 38 engaging 15 with the arm 23 of the member 17 and resting normally thereagainst. At the opposite end of the lever is a pawl 39 engaging with a ratchet-wheel 40 rigidly mounted upon the shaft 33 and pressed normally 20 against the ratchet wheel 40 by means of a leaf spring 41 secured to the lever by means of a screw 42.

The upper ends of the uprights 3 are laterally disposed and form bearings 43 in 25 which are mounted shafts 44. Rigid with the shafts are gears 45 in mesh with the worms 34 upon the shaft 33. The shafts 44 extend beyond the bearings 43 and have rigid pulleys 46, to each of which is secured 30 a line or cord 47. The line 47 passes under pulleys 48 rotatably mounted upon the table and has the opposite end secured to a shaft 49 mounted in extensions 50 of the uprights 3. A pawl 51 is carried by the shaft 49 and 35 engages with the ratchet-wheel 40, preventing the rotation of the ratchet-wheel in one direction.

The operation of the device is as follows: The roller 19 at the end of the arm 18 40 normally rests upon the top of the stack of sheets and holds the member 17 in a normal position. As the height of the stack is decreased the roller 19 no longer is in contact with the top of the stack though the 45 member 17 is still held in a normal position by the cam 29 until the rotation of the latter carries the recess 30 into a position such that the roller 24 on the arm 23 can slide into the recess and thus permit the member 17 to 50 swing downward about the shaft 16, the weight of the arm 23 being sufficient to operate the member. When the arm 23 is in a depressed position the lever 35 is in a similarly depressed position, the weight of 55 the lever maintaining the pin 38 in engagement with the arm 23, provided the position of the cam 31 is such that the extension 36 of the lever is located in the recess 32 of the cam. The arrangement of the cams upon 60 the shaft 26 is such that when the arm 23 of the member 17 is in the depressed position in the recess 30, the extension 36 of the lever 35 is also in engagement with the recess 32 of the cam 31. The lever 35 is actuated 65 by gravity, as the lower end is greater in

weight than the upper. As the lever 35 swings about the shaft 33 the pawl 39 is raised and slips into engagement with the next adjacent tooth of the ratchet wheel 40, the latter being held immovable in one direction by means of the pawl 51. As the cam 31 revolves with the shaft 26, the lever 35 is gradually raised by the lobe of the cam and in swinging about the shaft 33 the lever turns the ratchet-wheel 40 and consequently the shaft 33. This in turn through the worms and gears, rotates the shafts 44 and these, by means of the pulleys and the lines 47 raise the table, whereupon the roller 19 at the end of the arm 18 of the member 17 again comes into engagement with the top of the stack of sheets. The lobe of the cam 29 holds the member 17 in the normal position and thus the table will be raised only when the member is not held in its normal position either by the stack of sheets itself, or by the cam 29. Thus two conditions must be fulfilled before the table is raised: The stack of sheets must be lower than the roller 19, and the recess 30 of the 90 cam 29 must be in position to receive the roller 24.

Having thus described my invention, I claim as new, and desire to secure by Letters Patent:

1. In a device of the class described, a slideable table adapted to carry a stack of sheets, a member engaging the top of said stack and having its position controlled thereby, a lever engaging said member and controlled thereby, said lever being held in position against said member gravitationally, a cam adapted to operate said lever when the latter is swung from its normal position by the movement of said member, and means controlled by said lever for raising said table.

2. In a device of the class described, a slideable table adapted to carry a stack of sheets, a pivoted member directly engaging the top of said stack and having its position controlled thereby, a lever engaging said member and controlled thereby, said lever being held in position against said member gravitationally, a cam adapted to engage said member to operate the same, a second cam adapted to operate said lever when the latter is swung from its normal position by the movement of said member, and means controlled by said lever for raising said table.

3. In a device of the class described, a slideable table adapted to carry a stack of sheets, a pivoted member having arms, one of said arms being adapted directly to engage the top of said stack to limit the movement of said member, a cam engaging a second arm of said member and controlling the same, a pivoted lever engaging said second arm and controlled thereby, a second cam adapted to operate said lever to return the same to its 130

normal position, and means controlled by said lever for raising said table.

4. In a device of the class described, a slideable table adapted to carry a stack of sheets, 5 a pivoted member having arms, one of said arms being adapted to engage the top of said stack, a cam adapted to engage a second arm of said member to operate the same, a pivoted lever engaging said second arm, where- 10 by said lever is swung from its normal position when said member is operated, a second cam adapted to return said lever to its normal position, and means controlled by said lever for raising said table.
- 15 5. In a device of the class described, a slideable table adapted to carry a stack of sheets, a pivoted member having an arm engaging the top of said stack, a cam having a recess adapted to receive a second arm of said 20 member and a lobe adapted to operate the same, a lever having a pin engaging said second arm of said member, a second cam having a recess adapted to receive said lever, and a lobe adapted to operate the same, a 25 shaft, a line secured to said shaft and said table, and means operated by said lever for actuating said shaft to raise said table.
6. In a device of the class described, a slideable table adapted to carry a stack of sheets, 30 a pivoted member having arms, an arm of said member engaging the top of said stack, a cam having a recess adapted to receive a second arm of said member, and a lobe adapted to operate the same, a lever having 35 an extension and a pin, said pin engaging said second arm of said member, a second cam having a recess adapted to receive said extension, and a lobe adapted to operate said lever, a shaft having a ratchet, a pawl on 40 said lever engaging said ratchet, a worm on said shaft, a second shaft, a gear on said second shaft engaging with said worm, a pulley rigid with said second shaft, and a line secured to said pulley and said table.
- 45 7. In a device of the class described, a slideable table having a pulley and adapted to carry a stack of sheets, a pivoted member adapted to engage the top of said stack, a cam adapted to operate said member, a lever 50 controlled by said member and having a pawl, a shaft having a ratchet-wheel and a worm, said pawl adapted to operate said ratchet-wheel, a second shaft having a gear in mesh with said worm, a pulley, means for 55 preventing the rotation of said first shaft in one direction, and a line having an end secured to said pulley on said shaft and an opposite end fixed, said line passing over said pulley of said table.
- 60 8. In a device of the class described, a slideable table adapted to carry a stack of sheets, a pivoted member directly engaging the top of said stack and having its position controlled thereby, a lever engaging said 65 member and controlled thereby, said lever

being held in position against said member gravitationally, a cam adapted to operate said member, a second cam adapted to operate said lever when the latter is swung from its normal position by the movement of said 70 member, means controlled by said lever for raising said table, and endless lines having laterally disposed loops, similar runs of said loops being rigidly secured to said table.

9. In a device of the class described, a 75 slideable table adapted to carry a stack of sheets, a pivoted member having arms, one of said arms being adapted directly to engage the top of said stack to limit the movement of said member, a cam engaging a sec- 80 ond arm of said member and controlling the same, a pivoted lever engaging said second arm and controlled thereby, a second cam adapted to return said lever to its normal position, means controlled by said lever for 85 raising said table, and endless lines having upwardly disposed loops, similar upward runs of said loops being secured to said table.

10. In a device of the class described, a 90 slideable table adapted to carry a stack of sheets, a pivoted member having arms, one of said arms being adapted to engage the top of said stack, a cam adapted to engage a second arm of said member to operate the 95 same, a pivoted lever engaging said arm, whereby said lever is swung from its normal position when said member is operated, a second cam adapted to return said lever to its normal position, and endless lines having 100 upwardly disposed loops, similar upward runs of said loops being secured to said table.

11. In a device of the class described, a 105 slideable table adapted to carry a stack of sheets, a pivoted member having an arm en- 110 gaging the top of said stack, a cam having a recess adapted to receive a second arm of said member and a lobe adapted to operate the same, a lever having a pin engaging said second arm of said member, a second cam 115 having a recess adapted to receive said lever, and a lobe adapted to operate the same, a shaft, a line secured to said shaft and said table, and endless lines having upwardly dis- 120 posed loops, similar upward runs of said loops being secured to said table.

12. In a device of the class described, a slideable table adapted to carry a stack of sheets, a pivoted member having arms, an arm of said member engaging the top of said 125 stack, a cam having a recess adapted to receive a second arm of said member, and a lobe adapted to operate the same, a lever having an extension and a pin, said pin en- 130 gaging said second arm of said member, a second cam having a recess adapted to receive said extension, and a lobe adapted to operate said lever, a shaft having a ratchet, a pawl on said lever engaging said ratchet, a worm on said shaft, a second shaft, a gear

on said second shaft engaging with said worm, a pulley rigid with said second shaft, and endless lines having upwardly disposed loops, similar upward runs of each of said loops of said endless lines being rigidly secured to said table near an edge thereof.

In testimony whereof I have signed my

name to this specification in the presence of two subscribing witnesses.

JOSEPH KLEIDMANN.
